UNITED STATES PATENT OFFICE

FRED J. WESTROPE, OF DETROIT, MICHIGAN, ASSIGNOR TO THE MURRAY CORPORATION OF AMERICA, A CORPORATION OF DELAWARE

DOOR SPINDLE LOCK NUT

Application filed January 7, 1931. Serial No. 507,063.

This invention relates to improvements in door latches, more especially for the upholstered doors of automobiles, and more particularly to the means for securing the end 5 of the handle spindle on the inner side of the door.

The vehicle doors now in use upon automobiles consist generally in an outer panel and an inner panel of light sheet metal. 10 These panels form the inner and outer faces of the door; and the door latch includes a handle mechanism which has a spindle secured thereto which is inserted through the door from the outer side. The latch mechanism is usually contained between the two 15 panels where it is operatively engaged by the spindle.

In order to permit ready assembly and disassembly of the handle mechanism for the 20 purpose of repair or for the purpose of changing the latch mechanism, the inner end of the spindle is removably secured by a retaining screw which is inserted into the end of the spindle from the inner side of 25 the door, the head of the screw being flush with or exposed through the upholstery or trim on the face of the inner panel. In this type of mechanism unsatisfactory conditions develop. Since the head of the locking screw 30 is brought to bear directly upon the upholstery or trim, the head frequently pulls down into the fabric, damaging the same, and/or working loose and releasing the spindle.

35 The present invention contemplates a remedy for overcoming the defects mentioned above, by the provision of a locking means for retaining the screw, which also serves as a spacer for spacing the head of the screw 40 from the surface of the door substantially the thickness of the upholstery and thereby prevent damage to the upholstery.

Other objects of the invention, not at this 45 time more particularly enumerated, will become more readily apparent as the nature of the invention is better understood. The same consisting in the novel construction, combination of the parts shown in the accompanying drawings, in which:

50 Fig. 1 is a side elevation of an automobile

door having a latch mechanism embodying the principles of this invention, mounted thereon.

Fig. 2 is a fragmentary sectional view taken substantially along the lines 2—2 of 55 Fig. 1 and through the latch mechanism casing, the edge of the outer panel being shown in elevation in front of the plane of the section.

Fig. 3 is an enlarged fragmentary view, 60 taken substantially along the lines 3—3 of Fig. 2, with parts broken away.

Fig. 4 is a perspective view of the retaining screw head spaced and locking nut.

The outer panel is shown at 10 and the 65 inner panel or lock board is shown at 12, which are rigidly connected, as by cross members 14; and the latch mechanism is mounted on the lock board 12 as will be understood. The handle and associated mechanism 28 is 70 of well known construction and need not be described in detail herein further than that it includes a spindle 16 extending through an opening 18 in the panel 10. Secured to the outer end of the spindle 16 is a collar 30, 75 and disposed between the collar and the handle 28 is a compression spring 32 which positions the handle 28 relative to the escutcheon plate 34 in the conventional manner and prevents rattling there between. The 80 spindle is of the usual square section for engaging in squared bores in the latch mechanism parts which are to be rotated by the handle. The inner end of the spindle extends into the squared bore in the hub portion 56 85 of the latch roll-back cam. The hub is shouldered at both ends, and is rotatably supported in and held between the lock board 12 and the case plate 57 which may be mounted thereon as shown.

The inner end of the spindle 16 is provided with an axial bore 46, tapped to receive the threaded stem 48 of a retaining screw or stud 52. A locking nut and spacer 40 having an interiorly threaded shank or sleeve 42, 95 and a large flange 44 on its inner end, is provided for locking the retaining screw 52 to the spindle 16 and roll back cam 56 and for spacing the screw head 50 therefrom.

The upholstery 51, on the inner side of the 100

door usually comprises a stiff bottom layer 60 of cardboard or the like, a soft intermediate layer 66 of such material as cotton wadding, and the outer fabric or leather trim facing 68. The inner and bottom layers 66-60 are cut away at 62 to accommodate the flange 44 of the nut and spacer 40, and a hole 43 is provided through the outer fabric 68 for the sleeve 42.

10 The spindle is inserted into the door from the outer side and the inner end is inserted into the squared bore of the hub 56. The retaining screw 52, is applied by turning its threaded stem 48 through the nut and spacer 40 and into the tapped hole 46 in the inner end 54 of the spindle 16.

20 The head 50 of the screw is larger in diameter than the sleeve 42 of the nut and spacer so that the hole in the fabric is covered thereby; and the length of the sleeve 42 prevents the head 50 from turning down into or rubbing the upholstery and thereby working loose or damaging the upholstery when the spindle is rotated. The spacer and nut 40 serves also as a lock nut and prevents the retaining screw 52 from backing out of the taper bore 46 in the spindle 16.

25 While I have described but one illustrative embodiment of my invention, many alterations and omissions may be had without departing from the spirit of the same, as defined in the following claims.

I claim:

30 1. In a door of the class described having a finished panel disposed on its inner face, a latch mechanism between its faces, a latch operating spindle extending transversely through said door, a rotatable bushing journaled in the inner face of said door and receiving the end of said spindle, means for retaining the end of said spindle in said bushing comprising a screw member having a head disposed exteriorly of said finished panel and having a threaded shank extending through said finished panel and turned into the end of said spindle, a threaded sleeve member turned onto said screw shank and interposed between the head on said shank and said bushing and serving to space the said head from injurious contact with said finish panel and also to lock said screw member to said spindle and bushing.

35 2. In a door of the class described having a finish panel disposed on its inner face, a latch mechanism between its faces, a latch operating spindle extending transversely through said door, a rotatable bushing journaled in the inner face of said door and receiving the end of said spindle, means for retaining the end of said spindle in said bushing comprising a screw member having a head disposed exteriorly of said finish panel and having a threaded shank extending through said finish panel and turned into the end of said spindle, a threaded sleeve member turned on

40 to said screw shank and interposed between the head on said shank and said bushing and serving to space the said head from injurious contact with said finish panel and also to lock said screw member to said spindle and bushing, said sleeve having an enlarged end bearing against the end of said bushing and concealed beneath said finish panel and a reduced portion extending through said finish panel and concealed by the head of said screw member.

45 3. In a door of the class described having a finish panel disposed on its inner face, a latch mechanism between its faces, a latch operating spindle extending transversely through said door, a rotatable bushing journaled in the inner face of said door and receiving the end of said spindle, means for retaining the end of said spindle in said bushing comprising a screw member having a head disposed exteriorly of said finish panel and having a threaded shank extending through said finish panel and turned into the end of said spindle, a threaded sleeve member turned onto said screw shank and interposed between the head on said shank and said bushing and serving to space the said head from injurious contact with said finish panel and also to lock said screw member to said spindle and bushing, said sleeve having an enlarged end bearing against the end of said bushing and concealed beneath said finish panel and a reduced portion extending through said finish panel and concealed by the head of said screw member, and said finish panel having an undercut recess beneath its surface providing clearance for the enlarged end of said sleeve.

50 4. In a door of the class described having a finish panel disposed on its inner face, a latch mechanism between its faces, a latch operating spindle extending transversely through said door, a rotatable bushing journaled in the inner face of said door and receiving the end of said spindle, means for retaining the end of said spindle in said bushing comprising a screw member having a head disposed exteriorly of said finish panel and having a threaded shank extending through said finish panel and turned into the end of said spindle, a threaded sleeve member turned onto said screw shank and interposed between the head on said shank and said bushing and serving to space the said head from injurious contact with said finish panel and also to lock said screw member to said spindle and bushing, said sleeve having a laterally extending flange on its inner end providing a bearing against the end of said bushing and having its other portion reduced to a diameter less than that of the head of said screw member and extending through the surface of said finish panel.

FRED J. WESTROPE.
